United States Patent

Des. 237,207
Patented Oct. 14, 1975

237,207

COMPONENT FOR GRILLWORK, RAILINGS AND COLUMNS

Ellis De Loy Larson, 225 E. State Road,
Pleasant Grove, Utah 84062

Filed May 16, 1974, Ser. No. 470,354

Term of patent 14 years

Int. Cl. D25—02

U.S. Cl. D54—2 B

FIG. 1.

FIG. 2.

FIG. 3.

FIG. 4.

FIG. 1 is a perspective view, illustrating the design of the invention;

FIG. 2 is a front elevation;

FIG. 3 is a side elevation; and

FIG. 4 is a top plan view of the design.

The broken line showings of the rails in FIG. 1 are for illustrative purposes only and form no part of the claimed design.

I claim:

The ornamental design for a component for grillwork, railings and columns, as shown and described.
